UNITED STATES PATENT OFFICE.

THOMAS E. WILSON, OF FARMLAND, INDIANA.

FENCE.

SPECIFICATION forming part of Letters Patent No. 301,548, dated July 8, 1884.

Application filed July 24, 1883. (No model.)

To all whom it may concern:

Be it known that I, THOMAS E. WILSON, a citizen of the United States, residing at Farm-
land, in the county of Randolph and State of
5 Indiana, have invented certain new and useful
Improvements in Fences, of which the follow-
ing is a specification, reference being had
thereto to the accompanying drawings.

My invention relates to that class of fences
10 known as "farm-fences;" and it consists in cer-
tain improvements in the construction of the
same, as herein described and claimed.

The object of my invention is to construct
a combination straight-line and zigzag fence,
15 such as are commonly used for inclosing stock
animals, that shall be simple in construction
and durable.

In the accompanying drawings, Figure 1 is
a perspective view of a fence having my im-
20 provement. Fig. 2 is a rear view of the same.
Fig. 3 illustrates the metal pieces used at the
points of fastening posts and planks.

Referring to the drawings, in which similar
25 parts are indicated by similar letters, A rep-
resents the fence, having the posts *a*, to which
the upper planks or rails, *b*, are secured, and
the posts *a'*, to which the lower rails, *b'*, are
fastened, the said posts being preferably square
in cross-section.

30 In constructing the fence one or more of the
posts of a section of fence may be set in the
ground to a suitable depth, the others being
each placed on a stone foundation, *e*, the fence
being thus secured firmly in position. The
35 use of the stone foundations for the posts is
advisable in places where the ground is soft
or marshy. When placed on a stone, *e*, the
post is fastened and sustained by iron rods *e'*,
passing through apertures *f* in the lower part
40 of the post, the outer ends of said rods being
secured in the stone foundation. The posts
are so arranged that the lower planks, *b'*, se-
cured thereto, take a zigzag course, while the
upper planks, *b*, are fixed in a direct line.
45 As shown in Fig. 1, the middle post *a* is out
of a direct line passing through posts *a'*, and
two sets of rails *b'* extend from said post *a* to
posts *a'*. Two other posts *a* are set at points

about midway of the rails *b'*, and to the up-
per parts of these posts are fastened the up-
per rails, *b*, these being further secured and
braced by means of a cap-piece, *c*, fastened to
the top of central post *a* and to the upper-
most rail *b*, and a vertical piece, *c'*, fastened
to and connecting said rails *b*, as shown. The 55
metal pieces *d* are placed between the posts
and planks at points of fastening, so that
those parts are held somewhat apart, and no
moisture is retained between them. The said
pieces *d* are recessed or notched at their ends 60
to fit against the corners of the posts, and are
perforated for nails to pass through them.
They may be made round in section, as at *g*,
or rounded on the upper sides, *g'*, which are
most exposed to rain, &c. (See Fig. 3.) The 65
nails are driven through the planks and
through the apertures in the metal pieces *d*
into the posts, the corners of which fit in the
notches of said pieces.

By this construction of the fence all ani-
70 mals are effectually prevented from leaping
over the fence, either to encroach upon the
inclosed ground or to escape from the inclo-
sure, and a durable fence of simple construc-
tion is provided.

I claim—

1. In combination with the posts and hori-
zontal rails of a fence, the perforated notched
metal pieces *d*, placed between the posts and
the rails or planks at the points where such 80
parts are fastened together, substantially as
and for the purpose described.

2. In a fence, the combination of the posts
a and *a'*, the lower rails or planks, *b'*, placed
in a zigzag course, the upper rails placed in a 85
direct line and secured by cap-piece *c* and
vertical piece *c'*, and the notched metal pieces
placed between the posts and the rails at the
points of fastening, substantially as set forth
and described.

In testimony whereof I affix my signature in
presence of two witnesses.

THOMAS E. WILSON.
